UNITED STATES PATENT OFFICE.

WILLIAM HAAS, OF BROOKLYN, NEW YORK.

MACHINE FOR MAKING SHEET-METAL HINGES.

SPECIFICATION forming part of Letters Patent No. 399,038, dated March 5, 1889.

Application filed August 23, 1888. Serial No. 283,561. (No model.)

To all whom it may concern:

Be it known that I, WILLIAM HAAS, of Brooklyn, in the county of Kings and State of New York, have invented certain new and useful Improvements in Machines for Making Sheet-Metal Hinges, of which the following is a specification.

This invention relates to an improved machine for making sheet-metal hinges such as are used for boxes and other purposes; and the invention consists of a machine comprising the following elements: reciprocating pushers for feeding the blanks which form the leaves of the hinges against fixed stops, oscillating jaws which bend up the pintle portions of said leaves, intermittently-rotating rollers for feeding the pintle-wire, a reciprocating cutter for cutting off the pintle from said wire, a fixed eye for guiding said pintle into the pintle-sleeves of the leaves, and a reciprocating sleeve-closing jaw. The cutter and the sleeve-closing jaw are operated by eccentric cams on the driving-shaft, while the oscillating bending-jaws are operated by a crank-motion and the pintle-wire is fed forward by feed-rollers operated by suitable pinions, as will be fully described hereinafter, and finally be pointed out in the claims.

In the accompanying drawings, Figures 1 and 2 represent front elevations of my improved machine for making sheet-metal hinges, said figures showing the oscillating sleeve-bending jaws of the leaves respectively before and after the bending of the sleeves. Fig. 3 is a plan view of the machine; Fig. 4, a side elevation; Fig. 5, a vertical longitudinal section on line xx , Fig. 3. Figs. 6 and 7 are front views of the sleeve-bending jaws, drawn on a larger scale and showing the jaws before and after bending the sleeves of the leaves. Fig. 7^a is a detail side view of the bent-up sleeves of the leaves, showing the work accomplished by the bending-jaws; and Figs. 8 and 9 show, respectively, a vertical longitudinal section and a plan view of the leaf-feeding slide drawn on a larger scale.

Similar letters of reference indicate corresponding parts.

Referring to the drawings, A represents the supporting-frame of my improved machine for

making sheet-metal hinges, which frame is formed of a horizontal part, a , and upright standards a' a^2 , supported on said bracket a . The driving-shaft B is supported in suitable bearings below the part a and meshes by 55 bevel-gears a^3 a^4 with a vertical shaft, B' , supported in bearings of the part a and upright standard a' . The vertical shaft meshes again by bevel-gears a^5 a^6 with a horizontal shaft, B^3 , that is supported in bearings at the upper 60 ends of the upright standards a' and a^2 , as shown in Figs. 4 and 5. A crank, d , at the front end of the horizontal shaft B^3 is connected by a pivot-link, d' , with a cross-piece, d^2 , that is guided on the rails d^3 of the front 65 standard, a^2 , the crank d imparting vertically-reciprocating motion to said cross-piece d^2 .

To the cross-piece d^2 are pivoted at each side of the connecting-link d' two parallel links, d^4 , which are pivoted at their lower 70 ends to the apices of angular oscillating jaws $D D$, which are applied at their inner ends to a fixed pivot-pin, d^5 , that is supported in a fixed sleeve, d^6 , of the front standard, a^2 , as shown clearly in Fig. 5. The lowering of the 75 cross-piece d^2 produces the oscillating of the jaws $D D$ from their uppermost or initial position, as shown in Figs. 1 and 6, to their lowermost closed position, as shown in Figs. 2 to 7. The jaws are guided by arc-shaped cheeks 80 D' , attached to the front standard, a^2 . The ends of the jaws $D D$ are recessed according to the shape of the pintle-sleeves to be produced, the jaws being arranged to interlock in the same manner as the pintle-sleeves of 85 the hinge.

Immediately back of the jaws, when they are in their uppermost or initial position, are arranged horizontal guide-brackets E , on which are guided in ways $e e$ horizontally-reciprocating pushers E' , that pass below the lower end of upright blank boxes or receptacles E^2 , which are secured to the brackets E and of a shape corresponding to the blanks of the leaves from which the hinge is to be 95 made. The pushers E' are united at their rear ends by a transverse portion, the shank of which is attached to a slotted piece, E^3 , which is intermittently reciprocated by an eccentric cam, e' , on the upright shaft B' , 100

said cam engaging anti-friction rollers e^3 at the slotted piece E^3 , as shown clearly in Figs. 4 and 5, so as to impart steady positive motion to the pushers E' . By the forward motion of the pushers E' a blank is pushed forward from the lower end of each feed-box E^2 until arrested in its forward motion by a stop, e^3 , which is located immediately in front of each jaw D , as shown clearly in Figs. 8 and 9. The shape of the stop e^3 corresponds to the shape of the leaves, so as to retain them reliably in proper position for the action of the jaws. The downward motion of the jaws D bends the sleeve portions of the blanks 15 of the leaves into **U** shape, as shown in Fig. 7^a, the jaws carrying the leaves along until they interlock with each other when the jaws arrive at the lower end of their motion, as shown in Fig. 7. The leaves are retained in 20 this position by means of the cheeks D' and a small projecting shoulder, e^4 , (shown in Fig. 5,) while the jaws D are returned into raised position.

The pintle is supplied to the partly-closed 25 sleeves of the leaves by means of circumferentially-grooved feed-rolls $F F$, which are arranged at the lower part of the supporting-frame A , said rolls being operated by a pinion, f , on the driving-shaft B , back of the feed-rolls F , said pinion meshing with a pinion, f' , 30 on the shaft of one of the feed-rolls, as shown clearly in Figs. 1 and 5. The other feed-roll, F' , is carried along by friction with the driving feed-roll. Symmetrical portions of the 35 transmitting-pinion f are cut off, so that the remaining toothed portions serve to impart intermittent rotary motion to the feed-rolls, as required for the upward feed of the pintle-wire. The wire is passed along a guide-cheek, g , into a perforation, g' , of the reciprocating 40 cutter G , which cuts off the pintle from the wire by the backward motion of the cutter. Reciprocating motion is imparted to the cutter G by an eccentric cam, g^2 , on the upright 45 shaft B' and an anti-friction roller, g^3 , on the shank of the cutter, which roller engages a cam-groove of the cam g^2 , as shown clearly in Figs. 4 and 5. While the cutter G is in forward position the pintle-wire is fed upward 50 again into the opening of the same, so that the pintle before cut off is lifted and guided through a fixed eye, h , above the cutter into the partly-closed and interlocking sleeves of the leaves. When in this position, the pintle-sleeves are entirely closed around the pintle by a horizontally-reciprocating sleeve-closing 55 jaw, H , which is arranged immediately above the eye h and operated by an anti-friction roller, h' , on the shank of the sleeve-closer H and eccentric cam h^2 on the driving-shaft B' in the same manner as the leaf-pushers and the cutter, as shown in Figs. 4 and 5. The backward motion of the jaw H closes the 60 pintle-sleeves around the pintle and completes thereby the hinge, which is then removed from the machine. The operations of the different working parts of the machine are so timed by

their transmitting mechanisms that they take place in their regular order, so that a hinge is finished at each revolution of the driving-shaft. Any suitably-shaped hinge may be made by the machine, each shape of hinge requiring, however, feed-boxes and jaws of corresponding shape, while different sizes of hinges require different sizes of machines for 75 making the same. By my improved machine sheet-metal hinges for boxes of all kinds up to small door-hinges may be made in a quick, accurate, and reliable manner, so as to save considerable time and labor in putting them 80 together.

The operation of the machine is as follows: The feed-boxes are filled with properly-punched sheet-metal blanks for the leaves and are pushed forward by the pushers against 85 the stops and into the path of the bending-jaws, which bend at the pintle-sleeves and bring them down so as to interlock with each other ready to receive the pintle, which is cut off by the pintle-cutter and fed upward by 90 the wire-feed rollers into the partly-closed pintle-sleeves, after which the latter are closed around the pintle by the reciprocating closing-jaw, upon which the finished hinge is dropped from the machine.

Having thus described my invention, I claim as new and desire to secure by Letters Patent—

1. The combination of upright feed-boxes, horizontally-reciprocating pushers at the lower end of said feed-boxes, oscillating jaws, feed-rollers for the pintle-wire, a reciprocating pintle-cutter, an eye for guiding the pintle from the cutter into the partly-closed pintle-sleeves, and a reciprocating sleeve-closing 105 jaw, substantially as set forth.

2. The combination of upright feed-boxes, reciprocating pushers guided in ways below the feed-boxes, fixed stops in front of said feed-boxes, and oscillating bending-jaws moving at right angles to the pushers and jaws, substantially as set forth.

3. The combination, with oscillating jaws, of arc-shaped guide-cheeks for said jaws, wire-feeding rollers, a reciprocating pintle-cutter, a fixed eye above the same for guiding the cut-off pintle, and a reciprocating sleeve-closing jaw, substantially as set forth.

4. The combination of oscillating bending-jaws, arc-shaped guide-cheeks for said jaws, a shoulder intermediately between said cheeks, intermittently-rotating wire-feed rollers, a reciprocating pintle-cutter having an opening for the wire, a guide-eye above the cutter, and a reciprocating sleeve-closing jaw, substantially as set forth.

5. The combination of a rotary crank-shaft, a connecting pivot-link, a vertically-guided cross-piece, angular oscillating sleeve-bending jaws applied to a fixed pivot, and parallel pivot-links connecting said cross-piece and jaws, so as to impart oscillating motion to the jaw, substantially as set forth.

6. The combination of intermittently-ro-

tating grooved wire-feed rolls, a fixed cheek for guiding the wire, a horizontally-reciprocating cutter having an opening for the wire, a fixed eye above the cutter, and a horizontally-reciprocating sleeve-closing jaw, substantially as set forth.

In testimony that I claim the foregoing as

my invention I have signed my name in presence of two subscribing witnesses.

WILLIAM HAAS.
